(57) **CLAIM**

The ornamental design for an alcoholometer, as shown and described.

DESCRIPTION

FIG. 1 is a perspective view of an alcoholometer that illustrates the novel design;
FIG. 2 is a front elevational view of the alcoholometer of FIG. 1;
FIG. 3 is a rear elevational view of the alcoholometer of FIG. 1;
FIG. 4 is a left elevational view of the alcoholometer of FIG. 1;
FIG. 5 is a right elevational view of the alcoholometer of FIG. 1;
FIG. 6 is a top plane view of the alcoholometer of FIG. 1; and,
FIG. 7 is a bottom plane view of the alcoholometer of FIG. 1. The broken lines are for illustration only and form no part of the claimed design.

1 Claim, 7 Drawing Sheets

top left side perspective view

FIG. 1
top left side perspective view

FIG. 2
front elevational view

FIG. 3
rear elevational view

FIG. 4
left side elevational view

FIG. 5
right side elevational view

FIG. 6
top plane view

FIG. 7
bottom plane view
